UNITED STATES PATENT OFFICE.

STEPHEN J. MILLER, OF DANBURY, CONNECTICUT.

HAT-BRIM-PLATING MACHINE.

Application filed July 29, 1924, Serial No. 728,818.

This invention relates to machines for operating upon the brim of hats, and more particularly to machines adapted to iron down the edge portion of the brims to form a 5 "welt".

One of the objects of the invention is to provide a machine of the above nature practical and efficient and capable of meeting the requirements of practical use in a highly 10 satisfactory manner. Another object is to provide a machine of the above nature capable of turning out a high grade of work in a rapid and thorough manner. Another object is to provide such a machine of simple 15 yet strong and rugged construction, capable of withstanding long and hard service. Another object is to provide a machine of the above nature which is simply and conveniently operated. Other objects will be 20 in part obvious or in part pointed out hereinafter.

The invention accordingly consists in the features of construction, combination of elements, and arrangements of parts as will be 25 exemplified in the structure to be hereinafter described and the scope of the application of which will be indicated in the following claims.

In the accompanying drawings, in which 30 is shown one of the various possible embodiments of this invention,

Figure 1 is a top plan view of the machine showing a hat in position thereon.

Figure 2 is a section taken substantially 35 along the line 2—2 of Fig. 1, the lower portion of the standard being omitted;

Figure 3 is a section taken substantially along the line 3—3 of Fig. 2;

Figure 4 is a side view in detail of the 40 lower portion of the iron, and

Figure 5 is a front elevation of the iron shown in Fig. 4.

Similar reference characters refer to similar parts throughout the several views of 45 the drawings.

Referring now in detail to Figures 1 and 2 of the drawings, there is shown a support or table 10 upon which is carried the hat 11 to be operated upon. This table 10 is rotatable about a vertical axis, having a central downwardly projecting shaft 12 (shown in Fig. 3), which is rotatably supported in a vertical bearing 13, a suitable thrust collar 14 resting upon the upper edge 50 of the bearing 13 and carrying the weight of

the table 10 and the parts mounted thereon. Inside the hat 11 is positioned a block 15 which is preferably of small height, as shown, and snugly fits the interior of the lower portion of the crown. This block 15 60 supports and steadies the hat while the brim is being operated upon, and also centers the hat upon the table 10. The block 15 and the hat 11 held in position thereby are rotated with the table 10 through two or more pins 65 17 projecting from the table into the block. These pins 17 also serve to correctly position the oval hat so that its major and minor axes are properly related to the table and the operating tool or iron. 70

The bearing 13 in which the table 10 is supported and rotates is secured to the main frame 18 of the machine which is supported upon a suitable standard 19. As shown in Figure 3, the machine is driven from any suitable source of power through a pulley 20 fixed upon a transverse horizontal shaft 21 having bearings 22 on the frame 18. At the end of the shaft 21 opposite the pulley 20 is a worm 23 in mesh with a worm wheel 24. The worm wheel 24 is fixed upon a vertical pivot 25 which has a bearing 26 mounted upon the frame 18 and which at its upper end carries a pinion 27. Secured 80 against the bottom of the table 10 is a gear 28 meshing with the pinion 27. The table 10 is thus slowly rotated at constant speed through the worm and worm wheel 23 and 24 and the gears 27 and 28, the hat 11 rotating therewith. 85

Referring to Figure 2, there is secured to the frame 18 at 29 a stationary projecting bar 30. Slidably mounted upon this bar 30 is a box 31 at the right hand side of which, as viewed in Figure 2, is a projecting lug 31^a. Resting upon the top of the slidable box 31 is a carriage 32 which contacts the top surface of the box 31 at 32^a and 32^b, and which is pivotally connected therewith by a pivot pin 33 passing through the lug 31^a of the 90 box 31. From the description thus far, it will be seen that the box 31 is capable of sliding back and forth along the bar 30, and that the carriage 32 may swing about its vertical pivot pin 33, sliding upon the top of the box 31 at the surfaces 32^a and 32^b at which its weight is supported. 100

Secured to the bottom surface of the table 10 is a downwardly projecting flange 34 which is elliptical or oval in contour to 110

correspond with the oval shape of the hat 11. As best shown in Figure 3, mounted upon the right hand end of the carriage 32 are a pair of spaced rollers 35 and 36. These 5 rollers 35 and 36 bear against the outer surface of the rotating flange 34. Bearing against the inner surface of the rotating flange 34 is a third roller 37. This last roller 37 is carried upon a slide 38 which 10 is slidable along a bar 39 projecting from the carriage 32 and secured thereto at 40. The roller 37 is urged against the inner surface of the flange 34 by means of a compression spring 65 interposed between the 15 slide 38 and a nut 66 upon the right hand end of the bar 39.

Thus, as the table 10 and the hat 11, together with the flange 34, are rotated, the oval shape of the flange 34 causes the carriage 32 upon its sliding box 31 to move back and forth away from and toward the center of rotation of the table 10 and of the hat. This is accomplished by the rollers 35, 36 and 37 bearing against the flange 34 20 under the urge of the compression spring 65. The flange 34 being oval in contour, the degree of curvature of the portion of its surface engaging the rollers 35, 36 and 37, changes as the table rotates. The three rollers 30 are continually urged against the flange and the position of the roller 37 thus changes with respect to the rollers 35 and 36 with the changing curvature of the portion of the flange 34 in contact therewith. This results 35 in a swinging of the carriage 32 about its pivot 33, as will be more fully described hereinafter.

On the upper surface of the carriage 32 are a pair of brackets 43 in which is slidably 40 mounted a bar 44. This slidable bar 44 has a pair of upstanding ears 45 between which is pivoted upon a pin 47 an arm 46. As shown in Figure 2 the right hand end of this arm 46 carries a shell or iron 48, the 45 lower surface of which operates upon the brim of the hat 11. The iron 48 is removably secured to the arm 46 as by means of a bolt 49 passing through a lug 48^a of the shell or iron. The iron 48 thus bears by 50 gravity upon the table 10 or upon the hat brim thereon and may, if desired, be moved upwardly out of operative position by 55 swinging about the pin 47.

Secured to the side of the carriage 32 is 55 an outwardly projecting bracket 50 which has a downwardly projecting part 51. Pivoted by a pin 52 adjacent the lower end of the part 51 is an upright lever 53. This lever 53 extends from its pivot 52 upwardly 60 between a pair of pins 54 and 55 which project from the side of a plate 56 secured to the slide bar 44, above described. It will be seen that by manipulation of the lever 53, moving the same to the right or left 65 about its axis 52, as viewed in Figure 2,

the slide bar 44 is moved to move the iron 48 toward or away from the hat 11. Pivoted upon a pin 57 in the plate 56 is a latch 58, which is adapted to drop by gravity over the edge 50^a of the bracket 50 when the iron is moved away from operative position, by means of the lever 53, this latch 58 serving to lock the iron in such inoperative position. For convenient release of the latch 58, a handle 59 is pivoted upon the lever 53 at 60 and connected with the latch 58 by means of a light rod 61. Secured in the left hand end of the sliding bar 44 is a downwardly projecting pin 41 between which and the frame 18 is interposed a spiral tension spring 42. This spring 42 thus urges the bar 44 to the right and the iron 48 therewith toward the hat. The upstanding ears 45 on the bar 44 striking against the right hand guiding bracket 43 serve to limit the movement of the iron 48 toward the center of the table 10. The iron 48 is locked against movement toward the hat, under the urge of the spring 42, by means of the latch 58, as above described.

In the operation of the machine the brim of the hat 11 is shrunk or curled over by suitable means, as indicated at 11^a, before being placed in the machine. The block 15 is thereupon fitted inside the crown and the block and hat are then placed upon the table 10 and properly centered and positioned by the pins 17. A templet 62 which is preferably of light sheet metal is then placed upon the brim of the hat, its outer edge extending beneath the curled up portion of the brim 11^a. The inner edge of the templet 62 conforms substantially to the size and shape of the crown of the hat 11 at the band portion, and the templet is of substantially 95 the width and contour which it is desired that the finished brim have. The shell 48 is heated, for example by gas through a connection indicated at 63, and is adapted to iron over and down the curled up portion 110 of the brim closely against the surface of the templet 62, as shown in Figure 2, the portion 11^a of the brim being moistened to facilitate its shrinking into place under the action of the iron.

Considering now more particularly the construction of the iron 48, with reference to Figures 4 and 5, the portion of the operative surface thereof which first engages the hat brim is seen to comprise a curved 120 and dished side wall 48^b and a rearwardly sloping upper wall 48^c. This first portion of the iron is adapted to shrink the part 11^a of the brim smoothly and evenly down toward the surface of the templet 62. The 125 subsequently operating surface of the iron comprises a horizontal upper wall 48^d which bears down upon the folded over brim portion ironing it firmly into place. As has been described above, the iron 48 is con- 130

tinually urged toward the hat 11 by the tension spring 42 urging the slide bar 44 to the right. This movement of the iron to the right is limited by the surface 48^b thereof engaging the turned up edge portion 11^a of the brim and forcing it against the periphery of the templet and down against the upper surface of its outer edge.

As has been described, the carriage 32, due to the engagement of the rollers 35, 36 and 37 with the flange 34, partakes of a swinging movement about the pin 33 during rotation of the hat, the table 10 and the flange 34. The slide bar 44 carrying the iron 48 being mounted upon the carriage 32, the iron also partakes of this swinging movement about the pivot pin 33. The flange 34 is of substantially the same oval as the templet 62 and the iron 48 being swung about the pivot 33 in response to changes in curvature of the flange 34, the iron 48 is thus swung or adjusted about the pivot 33 in accordance with the changing curvature of the portion of the periphery of the templet 62 which is beneath the iron. This swinging or adjustment of the iron 48 is thus also substantially in accordance with the oval shape of the completed hat brim and of the hat crown. Such adjustment of the iron to correspond with the changing curvature of the periphery of the oval templet and brim effects the continual correct positioning of the iron so that the surface 48^b thereof irons the brim portion 11^a closely up against the periphery of the templet 62 at all portions thereof. The parts are so constructed and proportioned that the edge 48^e of the iron is at all times properly positioned with respect to the periphery of the templet 62, under the urge of the spring 42, so that this edge does not bind and scrape against the brim nor does it move away relative to the periphery of the templet 62 so as to leave undue clearance.

The above described adjustment of the carriage 32 and the iron 48 carried thereby in accordance with the changing curvature of the periphery of the brim of the hat may be better realized by reference to Figure 3. In this figure, the portion of the brim and templet of least sharp curvature is beneath the iron and the corresponding portion of the flange 34 is engaged by the three rollers 35, 36 and 37. As the table 10, the hat 11 and the flange 34 rotate in the direction indicated by the arrow, a portion of the flange 34 of sharper curvature moves between the rollers 35, 36 and 37, and the corresponding portion of sharper curvature of the brim and templet move beneath the iron. As this next succeeding portion of the flange 34 moves against the roller 36, due to the greater distance of this portion from the axis of the shaft 12, the roller 36 is urged outwardly away from the axis of the shaft 12.

At the same time, the roller 35 is permitted to move inwardly toward the axis of the shaft 12, due to a portion of the flange 34 of lesser distance from the axis of the shaft 12 coming into contact therewith. The 70 spring 65 continually maintains all three rollers in contact with the flange 34. Thus, at this portion of the movement of the flange 34 the carriage 32 is swung about its pivot 33 in a clockwise direction, as viewed in Figure 3. This results in a swinging of the iron 48 in the same direction, accomplishing a movement of the edge 48^e thereof in a direction away from the center of the hat. The edge 48^e is thus prevented from digging into and binding against the edge of the brim, and is maintained in substantially the proper relation with respect to the periphery of the templet 62. When a portion of the flange 34 of lesser degree of curvature and of lesser distance from the axis of the shaft 12 approaches the rollers 35, 36 and 37, the swinging of the carriage 32 and the iron 48 is in the opposite or counter-clockwise direction, as viewed in Figure 3, moving the edge 48^e of the iron inwardly toward the center of the hat the proper distance. The iron 48 is thus continually adjusted in accordance with the changing curvature of the oval and a smooth even ironing of the edge 11^a of the 95 brim over and down against the edge portion of the templet 62 is had.

From the above, it will be seen that there is herein provided a machine which embodies the features of this invention and attains the objects thereof, and that the same is well adapted to meet the requirements of practical use. The machine is sturdily constructed throughout, positive in action and capable of dependable operation with the 100 highest degree of efficiency.

As many possible embodiments may be made of the above invention and as many changes might be made in the embodiment above set forth, it is to be understood that all 110 matter hereinbefore set forth is to be interpreted as illustrative and not in a limiting sense.

I claim as my invention:

1. In a machine for operating upon hat brims, in combination, a rotating support for a hat, an oval templet adapted to be superimposed upon the brim of said hat, the edge of said brim being curled upwardly over the periphery of said templet, an iron adapted to iron said brim edge downwardly over the edge portion of said templet, means mounting said iron for sliding toward and away from said hat, spring means urging said iron to slide toward said hat, said iron having a surface forcing a portion of said hat brim laterally against the periphery of said templet, said templet thereby limiting the movement of said iron toward said hat, means for sliding said iron to an inoperative 130

position away from said hat, and means for locking said iron in said inoperative position against the urge of said spring.

2. In a machine for operating upon hat brims, in combination, a rotating support for a hat, an oval templet adapted to be superimposed upon the brim of said hat, the edge of said brim being curled upwardly over the periphery of said templet, an iron adapted to iron said brim edge downwardly over the edge portion of said templet, means mounting said iron for sliding toward and away from said hat, spring means urging said iron to slide toward said hat, said iron having a surface forcing a portion of said hat brim laterally against the periphery of said templet, said templet thereby limiting the movement of said iron toward said hat, and means mounting said iron adapted to permit manual swinging thereof into and out of operative relation to said hat.

3. In a machine for operating upon hat brims, in combination, a rotating support for a hat, an oval templet adapted to be superimposed upon the brim of said hat, the edge of said brim being curled upwardly over the periphery of said templet, an iron adapted to iron said brim edge downwardly over the edge portion of said templet, means mounting said iron for sliding toward and away from said hat, spring means urging said iron to slide toward said hat, said iron having a surface forcing a portion of said hat brim laterally against the periphery of said templet, said templet thereby limiting the movement of said iron toward said hat, and means adapted to adjust the position of said iron about a vertical axis to adjust the angular position of said surface thereof in accordance with the changing curvature of the periphery of said templet rotating thereby.

4. In a machine for operating upon hat brims, in combination, a rotating support for a hat, an oval templet adapted to be superimposed upon the brim of said hat, the edge of said brim being curled upwardly over the periphery of said templet, a supporting member slideable toward and away from said hat, an iron carried by said supporting member adapted to iron said brim edge downwardly over the edge portion of said templet, and spring means urging said supporting member to slide toward said hat, said iron having a surface forcing a portion of said brim laterally against the periphery of said templet under the urge of said spring, said templet thereby limiting the movement of said supporting member toward said hat, and said iron having a pivotal connection with said supporting member adapted to permit swinging of said iron thereon upwardly out of operative relation to said hat.

5. In a machine for operating upon hat brims, in combination, a rotating support for an oval hat, a frame, a supporting member mounted upon said frame for sliding movement toward and away from the axis of rotation of said hat and for swinging movement about a vertical axis, a slide carried upon said supporting member and slideable thereon toward and away from said hat, an iron carried by said slide and adapted to operate upon the edge portion of the brim of said hat, spring means urging said slide toward said hat and said iron thereon into engagement with said brim, and a connection between said supporting member and said rotating hat support adapted to move said supporting member to adjust the angular position of said iron in accordance with the changing oval of the portion of said hat rotating thereby.

6. In a machine for operating upon hat brims, in combination, a rotating support for an oval hat, a frame, a supporting member mounted upon said frame for sliding movement toward and away from the axis of rotation of said hat and for swinging movement about a vertical axis, a slide carried upon said supporting member and slideable thereon toward and away from said hat, an iron carried by said slide and adapted to operate upon the edge portion of the brim of said hat, spring means urging said slide toward said hat and said iron thereon into engagement with said brim, means limiting the movement of said slide upon said supporting member under the urge of said spring adapted to maintain said iron at a predetermined distance from the crown of said oval hat during rotation, and a connection between said supporting member and said rotating hat support adapted to move said supporting member to adjust the angular position of said iron in accordance with the changing oval of the portion of said hat rotating thereby.

7. In a machine for operating upon hat brims, in combination, a rotating support for an oval hat, an oval templet adapted to be superimposed upon the brim of said hat, ironing means adapted to iron the edge portion of the brim of said hat over the edge portion of said templet, said ironing means having a part urged laterally toward said hat and pressing a portion of said brim laterally against the peripheral edge of said templet, a pivotal support for said iron, and means controlled from said rotating support adapted during rotation thereof to swing said iron about said pivotal support and thereby adjust the angular position with respect to said templet of said part of said iron urging a portion of the brim laterally against the periphery of said templet, to maintain said part in proper angular rela-

tion to that portion of said curved templet periphery which is at any instant adjacent thereto.

8. In a machine for operating upon hat brims, in combination, a rotating support for an oval hat, an oval templet adapted to be superimposed upon the brim of said hat, ironing means adapted to iron the edge portion of the brim of said hat over the edge portion of said templet, said ironing means having a part urged laterally toward said hat and pressing a portion of said brim laterally against the peripheral edge of said templet, and a second part adapted to press the edge portion of said hat brim exterior of said last portion thereof down against the upper surface of said templet, a pivotal support for said iron, and means controlled from said rotating support adapted during rotation thereof to swing said iron about said pivotal support and thereby adjust the angular position with respect to said templet of said part of said iron urging a portion of the brim laterally against the periphery of said templet, to maintain said part in proper angular relation to that portion of said curved templet periphery which is at any instant adjacent thereto.

9. In a machine for operating upon hat brims, in combination, a rotating support for an oval hat, an oval templet adapted to be superimposed upon the brim of said hat, ironing means adapted to iron the edge portion of the brim of said hat over the edge portion of said templet, said ironing means having a part urged laterally toward said hat and pressing a portion of said brim laterally against the peripheral edge of said templet, and a second part adapted to press the edge portion of said hat brim exterior of said last portion thereof down against the upper surface of said templet, said first part of said ironing means acting upon said rotating hat brim prior to the operation thereof of said second part, a pivotal support for said iron, and means controlled from said rotating support adapted during rotation thereof to swing said iron about said pivotal support and thereby adjust the angular position with respect to said templet of said part of said iron urging a portion of the brim laterally against the periphery of said templet, to maintain said part in proper angular relation to that portion of said curved templet periphery which is at any instant adjacent thereto.

10. In a machine for operating upon hat brims, in combination, supporting means for the brim of a hat having a templet superimposed thereon, means adapted to rotate said support and said hat thereon, a tool adapted to iron the edge portion of said brim over the edge portion of said templet, means urging said tool toward the periphery of said templet, and means controlled from said rotat-

ing support adapted to adjust said tool in accordance with the changing curvature of the edge portion of said templet adjacent thereto.

11. In a machine for operating upon hat brims, in combination, supporting means for the brim of a hat having a templet superimposed thereon, means adapted to rotate said support and said hat thereon, means adapted to iron the edge portion of said brim over the edge portion of said templet, said tool being pivotally mounted, of means urging said tool toward the periphery of said templet, and means controlled from said rotating support adapted to adjust said tool about said pivot in accordance with the changing curvature of the edge of said templet adjacent thereto.

12. In a machine for operating upon hat brims, in combination, supporting means for the brim of a hat the edge portion of said brim being curled, a templet superimposed upon said brim inside said curl, means adapted to rotate said support and said hat thereon, a tool adapted to iron said edge portion of said brim down against said templet, and means controlled from said rotating support adapted to adjust said tool in accordance with the changing curvature of the edge portion of said templet adjacent thereto.

13. In a machine for operating upon hat brims, in combination, a rotating support for an oval hat, an oval templet adapted to be superimposed upon the brim of said hat, ironing means adapted to iron the edge portion of the brim of said hat over the edge portion of said templet, said ironing means having a part urged laterally toward said hat and pressing a portion of said brim laterally against the peripheral edge of said templet, and means controlled by a cam adapted to adjust the position of said ironing means as said oval hat rotates thereby to maintain the first acting edge portion of said part close in toward said templet and to prevent binding of said edge portion against the portion of said hat brim interposed therebetween and the edge of said oval templet.

14. In a machine for operating upon hat brims, in combination, a rotating support for an oval hat, an oval templet adapted to be superimposed upon the brim of said hat, ironing means adapted to iron the edge portion of the brim of said hat over the edge portion of said templet, said ironing means having a part urged laterally toward said hat and pressing a portion of said brim laterally against the peripheral edge of said templet, a second part adapted to press the edge portion of said hat brim exterior of said last portion thereof down against the upper surface of said templet, and means controlled by a cam adapted to adjust the position of said ironing means as said oval hat rotates thereby to maintain the first acting edge por-

- tion of said part close in toward said templet and to prevent binding of said edge against the portion of said hat brim interposed therebetween and the edge of said oval templet.
5. 15 In a machine for operating upon hat brims, in combination, a rotatable support for a hat, a tool for operating upon a curved portion of the hat, a cam rotatable with said support and having an oval shape substantially commensurate with the oval shape of the hat, a pivotal support for said tool, and means for periodically swinging said tool about its pivotal support, said means comprising a pair of spaced members contacting 10 with said cam at two spaced points thereof, and a third member yieldingly urged against said cam member and clamping a portion thereof between itself and said two spaced members.
10. 16. In a machine for operating upon hat brims, in combination, a rotatable support for a hat, a tool for operating upon a curved portion of the hat as the latter is rotated, and means for periodically tilting said tool 15 to prevent the latter from digging into the portion of the hat operated upon, said means comprising a pivotal support for said tool, a cam member rotatable with the hat, substantially oval-shaped, and having an exterior cam surface and an interior cam surface, a pair of spaced members connected with 20 said pivotal support and engaging one of said cam surfaces at two spaced points therein, and a member yieldably connected to said pivotal support and engaging the other surface of said cam member.
17. In a machine for operating upon hat brims, in combination, a rotatable support for a hat, a tool adapted to operate upon a curved portion of the hat, and means for 25 periodically tilting said tool to prevent the latter from digging into the portion of the hat operated upon as the curvature of the latter changes, said means comprising a pivotal support for said tool, a cam member, substantially oval-shaped, and having an exterior cam surface and an interior cam surface and rotatable with said support, a pair 30 of spaced members connected with said pivotal support and engaging the exterior cam surface of said cam at two spaced points 35 therein and a member yieldably connected with said pivotal support and engaging the interior surface of said cam.
18. In a machine for operating upon hat brims, in combination, a rotatable support for a hat having a templet superimposed upon the brim thereof, a tool adapted to iron the edge portion of said brim over the edge portion of said templet, and means for simultaneously adjusting the locus of operation of the tool with respect to said templet and periodically tilting said tool to prevent the tool from digging into the portion of the hat operated upon, said means including 40 a pivotal support for the tool, means for permitting the support to move toward or away from the axis of rotation of the hat, a cam member, substantially oval-shaped, and rotatable with said hat support, a pair of spaced members connected with said pivotal support and engaging said cam member at two spaced points therein, and means for yieldingly holding said spaced members in coaction wth said cam member.
19. In a machine for operating upon hat brims, in combination, a rotatable support for a hat having a templet superimposed upon the brim thereof, a tool adapted to iron the edge portion of said brim over the edge portion of said templet, a slide mounted for movement toward or away from the axis of rotation of the hat, a tool support pivotally mounted upon said slide, means urging said tool against the periphery of said templet, a cam member, substantially oval-shaped, and rotatable with said hat support, and a pair of spaced members connected to said tool support and in engagement with two spaced points on said cam member.
20. In a machine for operating upon hat brims, in combination, a rotatable support for a hat, a tool adapted to operate upon a curved portion of the hat, a slide mounted for movement toward or away from the axis of rotation of the hat, a tool support pivotally mounted upon said slide, means for periodically moving said slide toward and away from the axis of rotation of the hat and for swinging said tool support periodically about its pivot, and means mounting said tool upon said tool support and adapted to urge the tool toward the hat relative to said tool support.

In testimony whereof, I have signed my name to this specification this 12th day of July, 1924.

STEPHEN J. MILLER.
